TAKE-UP MOTION REGULATION DEVICE
FOR LOOMS

Hans Reifenberg, Viersen, Germany

Application April 14, 1936, Serial No. 74,252
In Great Britain March 17, 1936

1 Claim. (Cl. 139—309)

This invention relates to power looms of the kind comprising a cam-operated lever system operative to change periodically at a variable ratio the speed of the take-up motion in order to vary the weft density in repeat patterning, and the invention consists in the combination with a cam driven in known manner by means of a train of exchangeable gears, of a pair of double-armed levers interconnected by a link 10 which is adjustable in length, one of said levers being spring-controlled and adapted to co-operate with the drive of the take-up motion for regulating the speed thereof, and the other lever being supported on the cam by means of a thrust member in the form of an arm which is adjustable along a slot in the lever for varying the throw of the levers.

The mechanism obtained in this manner is very simple and allows a satisfactory regulation of the patterning as well as of the strokes of the levers.

For this purpose a lever by means of which the speed of the take-up motion is regulated is adapted to be rocked by a cam which receives rotary motion at a variable ratio from a driving shaft.

Figs. 1 and 2 of the accompanying drawing represent views at right angles to each other and partly in section of a device constructed according to the invention.

The loom is provided with a lever 14 which is rocked about a fulcrum 13 for regulating the speed of the take-up motion and thus the density of the weft. In order to vary this density periodically in repeat patterning, the regulating lever 14 is according to the invention controlled by a cam 6 which imparts a periodic rocking motion to the lever. The cam 6 acts on an aux-

iliary lever 10 which is pivoted at 9 to a rigid support and which is connected to the lever 14 by means of a link 12, the latter being adjustable in length by means of a screw coupling 16 for regulating the average speed of the take-up motion. An arm 8 is arranged as a thrust member between the cam 6 and the auxiliary lever 10. The connecting point of the arm with the lever 10 can be regulated for varying the throw of the lever 14. The connecting screw of the arm is for this purpose adjustable along a slot 11 in the lever. The arm 8 bears against the cam 6 by means of a roller 7. A spring 15, which acts on the lever 14, controls the lever system and maintains the roller 7 in contact with the cam.

The shaft 5 on which the cam 6 is mounted also carries a gear wheel 4 by means of which rotary motion is transmitted to the cam. A driving shaft 1 in the loom is fitted with a pinion 2 which transmits the motion to the wheel 4 by means of a train of speed-reducing gears 3, the wheels of the latter being exchangeable for varying the transmission ratio.

I claim:

In a take-up motion for looms, the combination of a spring-controlled rocking lever for regulating the speed of said motion, an auxiliary lever, a link of variable length connecting the two levers, a rotary cam, a driving shaft, a train of gears for transmitting motion at a variable ratio from the shaft to the cam, and an arm connected to the auxiliary lever and bearing against said cam for imparting rocking motion to the levers, said arm being adjustable along the auxiliary lever for varying the stroke of the levers.

HANS REIFENBERG.
